UNITED STATES PATENT OFFICE.

GUSTAVE CLUTHE, OF CINCINNATI, OHIO.

DEVICE FOR REMOVING CHAR FROM BARRELS.

999,208.

Specification of Letters Patent. Patented Aug. 1, 1911.

Application filed January 19, 1911. Serial No. 603,427.

To all whom it may concern:

Be it known that I, GUSTAVE CLUTHE, a citizen of the United States of America, and resident of Cincinnati, county of Hamilton, 5 and State of Ohio, have invented certain new and useful Improvements in Devices for Removing Char from Barrels, of which the following is a specification.

Barrels in which it is proposed to store whisky are charred interiorly before placing the whisky therein. When it is desired to reuse the barrel for storing a fresh supply of whisky, it is necessary to remove the old char completely.

15 My invention relates to a device for performing this operation.

The object of my invention is a machine for cutting the char from the interior of whisky barrels, quickly and efficiently.

20 Another object of my invention is a device of the character described in which the barrel may be readily inserted and removed.

These and other objects I attain by the means described in the specification and 25 illustrated in the drawings, in which,

Figure 1 is a view partly in elevation and partly in section of the device embodying my invention. Fig. 2 is a sectional view upon an enlarged scale of the shaft which 30 carries the brush and of the sleeves in which the shaft is mounted, the parts being broken out at the center and the ends being brought together to economize space. Fig. 3 is a detail sectional view of the means of mounting the barrel at one of its ends. Fig. 4 is a detail view of the shaft and its pulley. Fig. 5 is a detail view of the means of holding the barrel upon its support.

The barrel to be operated upon is supported at its closed end by a revolving clamp A, at its open end rests upon a roller B, and at its center is supported upon a roller D. Wire brush E is secured upon the end of a shaft F, which is rotated by a pulley f, 45 which is splined in said pulley, so that it is capable of having a reciprocation imparted manually to it, by the operator's grasping the handle f', which is secured rotatably upon shaft F. The barrel and the brush 50 are rotated in opposite directions.

I will now describe the device more in detail.

Shaft F is mounted in sleeves f² f³, which are secured between bearings f⁴ f⁵ f⁶ f⁷, 55 mounted upon the table F'. Sleeves f² f³ are slotted at f⁸ f⁹ to pass the handle f',

which, at one end engages a collar f¹⁰, mounted rotatably upon the shaft F, and at the other end carries a journal pin f¹¹, upon which the outer end of the shaft F is journaled. Shaft F has a slot f¹², which permits the shaft to reciprocate through the pulley f, while being rotated thereby. Pulley f is connected by belt F² with the main driving shaft G, which may be driven by motor g. 60 The brush E consists of a block e into which are driven flattened stiff steel rods e'.

Clamp, A, consists of a plate, a, having an annular flange a' and a rearwardly projecting shaft a². Shaft a² is mounted in 70 bearings carried by a standard A', and has secured upon it a pulley, to which rotation opposite to the direction of the rotation of pulley f is imparted by a cross belt A² connected to the main shaft G. Flange a' has 75 a series of hand screws a³ projecting through it. Screws a³ have secured to their inner ends leaf-springs a⁴, whose outer ends carry springs a⁵, which are secured to the flange a' and tend normally to draw the outer ends 80 of the springs a⁴ toward the flange a', thereby to facilitate the placing of the barrel in the clamp A.

Roller B at one end is swiveled in a lug d of the standard D', and at the opposite 85 end is swiveled in a rod d', whose lower end is connected to a foot lever D². A roller H holds the barrel against the clamp A. Roller H is mounted upon a plate h, which is slotted to pass bolts h', which lock the 90 plate h upon a bracket d² of the standard D'.

In operation:—A barrel being clamped in the holder, rotation is imparted to it in one direction, from the main shaft G, and 95 rotation is imparted to the brush E in the opposite direction. The operator grasping the handle f', inserts the brush into the open end of the barrel and gradually advances it into the barrel as the chars are 100 removed by the contact of the rods e' with the interior of the barrel, a contact which is increased in force by reason of the opposite rotation of the barrel and the brush. At the time of entering the brush into the 105 barrel, the operator, by placing his foot upon the lever D², raises the end of the barrel, and, as the brush advances into the barrel, the proper contact of the brush with the interior of the barrel is had by regulating the pressure upon the lever D², which 110 raises and lowers the barrel according to

the circumstances. When it is desired to remove the barrel, roller H is withdrawn from contact with the end of the barrel, by loosening bolts h', to permit the plate h to be moved backward; then the brush being moved to carry it out of the barrel, the barrel may be readily lifted out of the clamp A. In inserting a fresh barrel into the clamp, since the springs a⁵ hold the outer 10 end of the springs a⁴ adjacent to the flange a', it is seen that the springs do not interfere with the operator's inserting the closed end of the barrel into the clamp. By means of the hand screws a³, the clamp may be adjusted, so as to fit the end of the barrel 15 snugly.

What I claim is:—

1. In a device of the character described, the combination of a support for the barrel 20 to be cleaned, a clamp engaging the barrel and adapted to impart rotation to it, a

movable support for the end of the barrel opposite the clamp, means for regulating the position of the support, a shaft capable of reciprocation, means for rotating the 25 shaft, and a brush mounted upon the shaft and adapted to engage the interior of a barrel to be operated upon.

2. In combination with a device of the character described, a support for a barrel 30 to be operated upon consisting of a rotatable clamp for engaging the closed end of the barrel, a roller adapted to support the open end of the barrel, a fixed support for one end of the roller, a movable support for the 35 opposite end of the roller, and a lever for regulating the position of the movable end of the roller.

GUSTAVE CLUTHE.
